UNITED STATES PATENT OFFICE.

JOSEPH FINKELSTEIN, OF BROOKLYN, NEW YORK.

CORDING MACHINE.

Application filed April 22, 1926. Serial No. 103,715.

This invention relates to cording machines of that character wherein a plurality of threads are twisted together to form a relatively thick cord.

5 It is the primary object and purpose of my present improvements to provide such a machine including a revoluble twisting frame carrying a plurality of thread spools, operating means for said frame and means automatically acting when a thread breaks or the spool becomes exhausted to render said operating means inoperative.

10 It is also another object of the invention to provide a cording machine which is capable of operation at higher speeds than has heretofore been possible and to provide means whereby the independently rotatable thread spools may be easily and quickly mounted in or removed from the revoluble 15 twisting frame.

20 It is a further object of my invention to provide an improved construction of the twisting head at one end of the revoluble frame together with means for tensioning the cord strands and tightening the same into compact association in the cord.

25 Additional objects of my present improvements are to provide means for driving the cord receiving reel independently of the revoluble twisting head of the machine, to provide a reel operating means including a friction clutch to compensate for variations in the surface speed of rotation as the cord accumulates on the reel and thus maintain a constant uniform pull or tension on the cord, and to provide simple and effective means to 30 properly straighten and lay the threads and localize the point of twisting in the spinning head at which the threads are formed into the cord.

35 It is also a further general object of my present improvements to provide a machine of the above character which is relatively simple in construction, positive and reliable in its operation, and capable of manufacture at comparatively small cost.

40 With the above and other objects in view, the invention consists in the improved cording machine and in the form, construction and relative arrangement of its several parts as will be hereinafter more fully described, 45 illustrated in the accompanying drawings, and subsequently incorporated in the subjoined claims.

50 In the drawings, wherein I have illus-

trated one satisfactory and practical embodiment of the invention, and in which similar reference characters designate corresponding parts throughout the several views,—

Figure 1 is a top plan view of my improved cording machine;

Fig. 2 is a side elevation thereof;

Fig. 3 is a front end elevation;

Fig. 4 is a detail side elevation showing the drive means for the cord receiving reel;

Fig. 5 is an enlarged detail longitudinal section through one end of the revoluble twisting frame showing the manner of mounting the thread spool therein;

Fig. 6 is a sectional view taken on the line 6—6 of Fig. 5;

Fig. 7 is a transverse sectional view taken substantially on the line 7—7 of Fig. 1;

Fig. 7^a is a detail section taken on the line 7^a—7^a of Fig. 7;

Fig. 8 is an enlarged vertical sectional view through the twisting head of the revoluble frame and showing the cord tensioning means;

Fig. 9 is a detail vertical section of the feed means for directing the individual threads to the twisting head;

Fig. 10 is a detail vertical sectional view illustrating the slip friction drive clutch for the cord receiving reel;

Fig. 11 is a detail elevation of the driving head for the reel;

Fig. 12 is a detail elevation of the reel driving sprocket and the friction ring carried thereby, and

Fig. 13 is a detail elevation of the friction clutch plate.

Referring in detail to the drawings, the several parts of the machine are suitably mounted and arranged upon a frame structure generally indicated at 5. On opposite ends of this frame structure standards 6 are mounted, each of said standards being provided with a suitably formed hub extension 7 to receive a shaft extension 9 at one end of the revoluble twisting frame 8. Preferably, suitable ball bearings indicated at 10 are interposed between the frame ends and the bearing hubs 7 of the standards 6. One of the frame shaft extensions 9 has a longitudinally extending bore 11 through which the individual threads pass to a sheave 12 rotatably mounted in the twisting head 13 threaded or otherwise detachably connected to the end of the frame shaft 9. After pass-

ing over this sheave, the cord formed by the twisted threads is drawn through an opening 14 in the end wall of the head 13 as will be hereinafter explained.

The frame 8 is in the form of a narrow elongated structure having parallel side portions connected at spaced intervals by transverse webs 15, thereby dividing the frame structure into a plurality of sections. In 10 each section of the frame, a thread spool is adapted to be mounted for independent rotation about an axis coinciding with the axis of revolution of the frame 8.

As herein shown, the sleeve or tubular core 16 of each thread spool is adapted to be removably fixed upon a shaft 17, said shaft having a wheel or disc 18 adjacent one of its ends against which one end of the core 16 is adapted to abut and being also provided with spaced cylindrical enlargements 19 snugly fitting within said tubular core. Adjacent its other end the shaft 17 is provided with a threaded section 20 to receive the clamping nut 21 which is adapted to be adjusted thereon into engagement with the other end of the spool core 16 whereby the latter is thus rigidly held or fixed between said nut and the disc 18 against longitudinal or rotative movement relative to the shaft 17.

Each of the transverse webs 15 of the frame 8 is centrally provided with a V-shaped recess 22 opening upon one edge thereof and leading to a bearing seat 23 which receives the opposed ends of the shaft 17 of adjacent thread spools. The shaft ends are removably held upon the bearing seats 23 by means of the locking members 24 pivotally mounted upon the transverse webs 15 as at 25, each of these members is formed with a concave bearing surface 26 for engagement upon the upper sides of the shaft ends and is provided with an extension 27 adapted for engagement in a recess 28 in the edge of the web 15 of the frame. A yoke member 29 straddles the web 15 and has its arms pivoted thereto as at 30 and carries a set screw 31 which is adapted to be adjusted into engagement with a recess or socket 32 provided in the edge of the extension 27 of the locking member 24 as shown in Fig. 7 of the drawings. Thus, this member 24 is securely fixed in position against pivotal movement with respect to the revolute frame and the ends of the spool shafts 17 are held upon their bearing seats.

The wheel or disc 18 is provided with a peripheral groove 33 adapted to receive a spring pressed brake member 34 mounted in an angularly offset arm 35 of the member 24. If desired of course, suitable means may be provided for adjusting the tension of the spring 36 so as to regulate braking pressure of the member 34 upon the walls 60 of the groove 33. In addition to this brak-

ing means, I may also provide the members 37 mounted upon one side of the frame 8 and resiliently urged inwardly and upwardly with their free ends in bearing contact against the thread on the spool core 16. 70

Each of the thread spools carries means for automatically actuating a suitable clutch device to disconnect the drive means for operating the frame 8 when a thread spool becomes exhausted. This means, as illustrated in the drawings, comprises a pivoted dog 38 pivotally mounted as at 39 upon the outer side of the disc or wheel 18 and having a tapering end portion 40 projecting inwardly through an opening 41 in said disc and normally held by the pressure of the thread indicated at T in contact with the spool core 16. A spring 42 connected with the outer end of the lug 38 tends to rock said dog upon the pivot 39 and move the same outwardly through the opening 41 when the pressure of the thread on the part 40 thereof is released. Said dog will thereby be positioned in the path of the free end of an arm 43 pivoted at its other end as at 44 on the web 15 of the frame. This pivoted arm has a lug 45 intermediate of its ends adapted to engage behind a head 46 on one end of a rod 47 which is slidably mounted in a guide sleeve 48 fixed in one side of the frame 8. This rod 47 is normally urged outwardly to the position shown in dotted lines in Fig. 7 by means of the spring 49. When said rod 47 is pushed inwardly to the position shown in full lines in said figure, the head 46 engaging lug 45 first lifts the arm 43 slightly against the action of the spring 50 connected with the free end of said arm, said spring then returning the arm to normal position and engaging the lug 45 behind said head, thus holding the rod 47 in the position shown in full lines in said figure, which is the normal position thereof in the operation of the machine. However, when the thread on the spool becomes exhausted and the dog 38 is moved outwardly through the opening in the wheel or disc 18, it will be understood that said dog as shown in dotted lines in Fig. 7 will engage the free end of arm 43 and lift the same, thereby releasing the rod 47 which is returned to its normal position by a spring 49 so that the outer end of said rod, as shown in dotted lines, will extend beyond the side of the frame in position to actuate means whereby the drive clutch for frame 8 is released. 110 115 120 125

In the lower part of the frame 5, the longitudinally extending driving shaft 51 is journaled and has a drive wheel 52 loosely mounted upon one end thereof driven by belt 53 from a suitable source of power such as an electric motor. This drive wheel 52 is adapted to be fixedly secured to the shaft 51 by a clutch device of any approved form indicated at 54. The movable element of this 130

clutch device is connected with a lever 55 intermediate of its ends, said lever being pivoted at one end thereof as at 56 and having a bar 57 pivotally connected to the other end 5 thereof extending longitudinally along one side of the frame 5 and slidably mounted in a bracket 58 on said frame. Between this bracket and a collar 59 fixed to the bar 57 a spring 60 is interposed and acts to normally hold the movable element of the clutch device in its released position. A vertically positioned hand operated lever 61 pivoted at its lower end as at 62 on the frame is also pivotally connected as at 63 with the bar 57.

In suitable spaced bearings 64 on the frame 5 a rock shaft 65 is mounted. An arm 66 is fixed to one end of this shaft and a spring 67 attached to said arm tends to normally hold the same in a notch 69 provided in the upper edge of an arm 68 pivotally connected as at 70 to the upper end of the lever 61. The several bearings 64 for the rock shaft are connected by a longitudinally extending rail 71 and upon one of said bearings a locking dog 72 is pivotally mounted intermediate of its ends and is adapted to engage at one of its ends with a shoulder 74 on the periphery of a collar 73 fixed on the rock shaft 65. This rock shaft also carries a plurality of inwardly extending arms 75 in line with the several rods 47.

From the above description, it will be understood that the clutch is thrown in to connect drive wheel 52 with shaft 51 by shifting the upper end of lever 61 to the right from the position shown in Fig. 2. The notch or recess 69 is thus moved to a position where it receives the arm 66 on shaft 65, and in such position the other inwardly extending arms 75 carried by the rock shaft occupy the position indicated in dotted lines in Fig. 7 of the drawings. When one of the rods 47 has been projected outwardly from the side of the frame upon the exhaustion of one of the thread spools in the manner above explained, said projecting end of the rod strikes the arm 75, thereby rocking the shaft 65 against the action of spring 67 and disengaging arm 66 from the notch 69 in the arm 68. A leaf spring 76 on the under side of rail 71 bearing upon the end of the locking dog 72 engages the latter with the shoulder 74 on the collar 73, thus holding the rock shaft against reverse rotation under the action of spring 67. The spring 60 may thus act to shift the bar 57, thereby actuating lever 55 to move the movable element of the clutch device 54 to its released position. Thus the transmission of power to the shaft 51 is interrupted and the operation of the machine automatically stopped so that the exhausted thread spool can be readily removed and a new spool secured upon the shaft 17.

From the several thread spools the threads T are led through a suitable guide 77 on one side of the frame 8 and also through guide openings provided in the several webs 15 of the frame. Upon the web 15 at one end of the frame there is mounted a device automatically operating upon the breakage of any one of the several threads to actuate rock shaft 65 and release the drive clutch as above explained. This device in a preferable embodiment thereof is shown in detail in Figs. 7 and 7^a and may be explained as follows:

Upon one side of the bracket plate 78 fixed to the web 15 a plate 79 is secured and is provided with a series of spaced parallel lugs 80 and between these lugs the fingers 81 are pivotally mounted at one of their ends upon a rod 82. Guide thimbles 83 for the threads are fitted into coinciding openings in the bracket 78 and plate 79 and rigidly fixed in place by means of the set screws 84 threaded in the bracket plate. In their normal positions, the free ends of the pivoted fingers 81 engage stop pins 85 which limit the swinging movement of said fingers towards the plate 79 and support the several fingers at a slight outward inclination with respect to the plane of said plate as shown in Fig. 7^a of the drawings. These free end portions of the fingers also have openings 86 therein through which the respective threads extend as shown in Fig. 7 of the drawings. So long as there is sufficient tensile pull on the several threads, the pivoted fingers 81 are held in their normal position shown in Fig. 7^a. In the event, however, that any one of the threads should break, the guide finger through the opening of which said thread extends, is released and in the high speed revolution of the frame 8 the said finger will be thrown outwardly by centrifugal force to the position indicated in dotted lines in Fig. 7 of the drawings so that its free end will then be disposed in the path of one of the arms 75 on the rock shaft 65 and will operate said rock shaft to release the driving clutch connection to the shaft 51, thus stopping the operation of the machine in the manner heretofore explained.

In order to maintain a proper tension upon the individual threads after they are drawn through the several guide fingers 81 and as they are fed to the twisting head of the frame 8, a roller 87 is mounted in one end of a channelled supporting bar 87' fixed in the frame 8, the surface of said roller being covered with emery cloth as indicated at 88. In the rear of this roller and in spaced relation thereto, a second guide roller 89 for the threads is mounted. As shown in Fig. 9 of the drawings, the individual threads first extend over and around the roller 87, the emery cloth facing thereof maintaining said threads in proper spaced relation, the

said threads then extending inwardly and around the guide roller 89 from which they extend in gradually converging relation into and through the bore 11 of the shaft extension 9 of the revolving frame and over the sheave 12 mounted in the twisting head 13. At this point, namely, upon the sheave 12, the several threads are twisted together upon each other and thereby form the cord indicated at C.

At opposite sides of the twisting head 13, longitudinally extending bracket arms 90 are fixed to the machine frame and project beyond the head 13. In the ends of these arms a pair of guide sheaves 91 and 92 respectively, are rotatably mounted. The cord C after leaving the sheave 12, passes downwardly around the sheave 91 and around roller 93 fixed on shaft 94 journalled in spaced bracket arms 95 fixed to the end of the machine frame. This roller 93 is also provided with a facing of emery cloth and from the same the cord C extends upwardly and around the other sheave 92 and hence downwardly through a transversely travelling guide 96 to a suitable reel to be later referred to. Spaced lever bars 97 are pivoted at their upper ends as at 98 to the respective bracket arms 90 and between the lower ends of these levers a roller 99 is rotatably mounted and is yieldingly urged by a suitable spring 100 connected with the lever bars 97 and bearing against standards 6 upon the cord C as it passes upwardly around roller 93.

Upon the brackets 101 projecting from the end of the machine frame 5, standards 102 are mounted. In the upper end of one of these standards a stud shaft 103 is rigidly fixed. Upon this stud shaft a reel supporting head 104 is rotatably journalled, said head being provided with an externally threaded hub extension 105. This reel head is preferably in the form of a disc 106 having radially extending arms 107. The outer face of said disc is formed with an annular depression or recess 108 and inwardly thereof with a beveled annular face 109. An annular plate 110 is adapted to be engaged upon the hub extension 105 and one side face thereof is also formed with an annular depression or recess 111 and with the beveled annular surface 112 which are adapted to be opposed to the corresponding surfaces 108 and 109 of the disc 106. Between said disc and the annular plate and spacing the same apart the ring 113 is arranged. This ring, the disc 106 and the plate 110 are provided with coinciding openings to receive the pins 114 whereby the parts are locked together against relative rotation. A nut 115 is threaded upon the hub extension 105 against the outer side of the plate 110.

The driving sprocket 116 for the reel 121 has an internal annular ring 117 of leather

or other friction material connected to said sprocket by means of a plurality of radially extending pins 118. This leather annulus is positioned between the plate 110 and the disc 106, the opposite sides thereof being frictionally engaged with the surfaces 111 and 108 respectively of said plate and disc. Thus, it will be understood that this leather ring or annulus 117 acts as a friction slip clutch member for transmitting rotation from the drive sprocket 116 to the reel head.

In the other of the standards 102 a clamping screw 119 is threaded and has a clamping head 120 swiveled on its inner end. The reel shown at 121 may be of the usual form consisting of the cruciform end members connected by a suitable core. The radially projecting members at one end of the reel are provided with recesses or sockets therein indicated at 122 in Fig. 11 to receive the laterally projecting arms 107 of the head 106. If desired, the arms of the reel may be provided with adjustable screws indicated at 123 for binding engagement against the arms 107. After thus positioning the reel, the screw 119 is then adjusted to engage the clamping head 120 with the other end of the reel and thus rigidly clamp and secure the reel between said head and the lead 106.

One end of the shaft 94 has a beveled gear 124 fixed thereto meshing with the gear 125 on the power transmission shaft 126. A countershaft 127 has two gears 128 of different diameters adjustably mounted thereon and adapted for engagement respectively with the spaced gears 129 and 130 fixed on the shaft 126 whereby the latter shaft may be driven at different speeds. Countershaft 127 is driven by the counterchain connection 131 from a shaft 132 which in turn is driven by the chain or belt connection 133 with the operating shaft 51.

The drive sprocket 116 for the cord winding reel is connected by the endless sprocket chain 134 with a sprocket 135 fixed upon the shaft 94.

For the purpose of winding the cord evenly on the reel 121, the cord guide 96 is moved transversely back and forth for the length of the reel. For this purpose, I have herein shown said guide fixed to an endless belt or chain 136 engaged at its opposite ends with suitable sprockets on shafts 137 mounted in a bar 138 fixed at its ends to the brackets 95. One of these shafts 137 is rotatably mounted in said bar and has a gear 139 secured thereon meshing with the pinion 140 fixed to a second shaft suitably mounted on said bar 138. The latter shaft is also provided with a worm gear 141 which is in constant mesh with a worm 142 on the shaft 94. Thus, it will be understood that the cord guide 96 is continuously moved back and forth for the entire length of the reel 130

and in synchronized relation with the rotation of said reel. As the cord accumulates upon the reel so that the surface speed of rotation of the reel gradually changes to the speed of rotation of the driving sprocket 116 for said reel, the leather friction ring 117 fixed to the sprocket will slip between the opposed faces of the reel head and the plate 110, thus automatically compensating for said differences in speed of rotation and maintaining a substantially constant uniform tensile pull on the cord.

From the foregoing description considered in connection with the accompanying drawings, the construction, manner of operation and several advantages of my improved cording machine will be clearly understood. While in the drawings I have shown a machine having a four spool capacity, it will be understood that the machine may be constructed to operate with a greater or less number of the thread spools as desired. When any one of the spools becomes exhausted, by merely releasing the yoke member 29 and moving the same to the position shown in dotted lines in Fig. 7, the member 24 may be swung outwardly away from the spool shaft, thus permitting of the easy and quick removal of the exhausted spool from the frame 8. Also by providing the automatically operating means for stopping the machine when a spool becomes exhausted or a thread breaks, imperfections in the product and waste of materials is reduced to a minimum. For the purpose of protecting the attendant or operator, I may provide a guard of wire screen or other similar material indicated at 143 extending over the revolving frame 8 and suitably secured to the main frame 5 and the end standard 6. Of course this screen will be provided with suitable hinged or movably mounted sections so that access may be had to the several thread screws.

While I have herein shown and described an embodiment of my present improvements which has given excellent results in practice, it will nevertheless be understood that the several novel features of the machine are susceptible of embodiment in various other alternative forms, and I therefore, reserve the privilege of resorting to all such legitimate changes in the form, construction and relative arrangement of the several elements as may be fairly embodied within the spirit and scope of the invention as claimed.

I claim:

1. In a cording machine, a revoluble twisting frame, thread spool shafts removably mounted at their ends in said frame, members pivotally mounted upon the frame for releasable bearing engagement upon one end of the respective shafts, a head fixed on each spool shaft, and a brake element on each of said pivoted members for frictional engage-

ment with the periphery of the respective spool shaft heads.

2. In a cording machine, a revoluble twisting frame, a plurality of thread spool shafts mounted in said frame in alignment with each other, members pivotally mounted upon the frame and having releasable bearing engagement upon the ends of adjacent spool shafts, additional means on the frame for securing said members against pivotal movement, a head fixed on each of the spool shafts, and resiliently yieldable braking elements carried by said pivoted members frictionally engaging the peripheral surfaces of said spool shaft heads.

3. In a cording machine, a revoluble twisting frame, a plurality of thread spool shafts mounted in said frame for independent rotation in axial alignment with the axis of revolution of said frame, means for clamping a thread spool on each shaft including a head fixed on the shaft, and means for removably retaining the spool shafts in operative position in the frame including members pivotally mounted on the frame for bearing engagement upon the ends of adjacent spool shafts, means for locking said members to the frame against pivotal movement, and means carried by said members for applying a frictional braking pressure against the peripheral faces of the heads on said spool shafts.

4. In a cording machine, a revoluble twisting frame, a plurality of thread spool shafts mounted in said frame for independent rotation in axial alignment with the axis of revolution of said frame, means for clamping a thread spool on each shaft including a head fixed on the shaft and having a continuous groove in its periphery, means for removably retaining the spool shafts in operative position in the frame including members pivotally mounted on the frame for bearing engagement upon the ends of adjacent spool shafts, means for locking said members to the frame against pivotal movement, and braking elements mounted upon said pivoted members and having yieldable frictional engagement with the walls of the grooves in the respective heads on said spool shaft.

5. In a cording machine, a revoluble twisting frame, means for removably mounting a plurality of thread carrying spools in said frame for independent rotation, drive means for said frame including a shiftable clutch member, latch means for holding the clutch member in effective driving position, and means for actuating said latch means to release the clutch upon exhaustion of the thread on any one of the spools, said means including a rock shaft having a plurality of arms fixed thereon, spring projected rods mounted in the twisting frame to cooperate with the respective arms, means

for holding said rods in a retracted position in the frame, and devices controlled by the thread on the respective spools and automatically operated upon the exhaustion of the thread therefrom to actuate said last-named means whereby one of the rods is projected to engage one of the arms on said rock shaft and actuate said latch means to release the clutch and disconnect the twisting frame operating means therefor.

6. In a cording machine, a revoluble twisting frame, a plurality of thread carrying spools removably mounted in said frame for independent rotation, operating means for said frame and a shiftable clutch for effecting a driving connection between said means and the frame, means for shifting said clutch to its released position, a latch for holding the latter means against operation, and means for automatically actuating said latch upon the breakage of any one of the threads, said means including a rock shaft having an arm fixed thereon, a plurality of pivoted fingers mounted on the twisting frame and having openings through which the respective threads are drawn whereby said fingers are held in a normal position by the tension of the threads, and said fingers being independently projected by centrifugal force upon the breakage of one of the threads into the path of movement of the arm on said rock shaft whereby the latch means is actuated to release said

clutch and disconnect the frame from its operating means.

7. In a cord twisting machine, a revoluble frame, means for mounting a plurality of thread carrying spools in said frame for independent rotation, a twisting head fixed to one end of the frame, means mounted in the axis of said frame for directing the threads from said spools to the twisting head, operating means for said frame, a cord receiving reel receiving the cord from said twisting head, and means for driving said reel at variable speeds relative to the speed of revolution of said frame.

8. In a cord twisting machine, a revoluble frame, means for mounting a plurality of thread carrying spools in said frame for independent rotation, a twisting head fixed to one end of the frame, means mounted in the axis of said frame for directing the threads from said spools to the twisting head, operating means for said frame, a cord receiving reel receiving the cord from said twisting head, said twisting head having means mounted therein for permanently localizing the point of twist of the threads, and means for driving the cord receiving reel at variable speeds relative to the speed of revolution of said frame.

In testimony that I claim the foregoing as my invention, I have signed my name hereto.

JOSEPH FINKELSTEIN.
